MECHANICAL STOKER

Herbert E. Preston, Philadelphia, and Joseph S. Bennett, Merion, Pa., assignors to American Engineering Company, Philadelphia, Pa., a corporation of Pennsylvania

Application April 14, 1936, Serial No. 74,260

8 Claims. (Cl. 110—44)

This invention relates to mechanical stokers, and more particularly to stokers of the multiple retort underfeed type.

One object of the present invention is to provide a generally improved and simplified stoker of the stated character.

Another object is to provide each stoker retort with an improved arrangement of fuel feeding and distributing elements.

A further object is to provide in stokers of the stated character an improved and simplified front wall construction.

A still further object is to provide an improved mounting for the ram boxes of the stoker which house the main fuel feeding rams.

A still further object is to provide improved stoker retort and ram box cap constructions.

Other and further objects will become apparent as the description of the invention progresses.

Of the drawings:

Fig. 1 is a longitudinal sectional view diagrammatic in part taken through one of the retorts of an underfeed stoker, showing various of the improvements comprising the present invention.

Fig. 2 is a sectional elevational view taken substantially along line 2—2 of Fig. 1.

Fig. 3 is a sectional elevational view taken substantially along line 3—3 of Fig. 1.

Fig. 4 is an elevational view, partly in section, and with certain parts removed to show the construction of the interior of the front wall of the stoker, said view being taken substantially along lines 4—4 of Fig. 1.

Fig. 5 is an elevational view, partly in section and with some of the parts removed, showing the structure of the exterior of the front wall of the stoker, said view being taken substantially along line 5—5 of Fig. 1.

Fig. 6 is an enlarged sectional view taken through the front wall of the stoker showing certain details of construction thereof.

Fig. 7 is a sectional plan view taken substantially along line 7—7 of Fig. 6.

Fig. 8 is a sectional view taken substantially along line 8—8 of Fig. 6.

Fig. 9 is a side elevational view taken through the stoker, partly in section and with certain parts removed to show the structural framework of the stoker and the supports therefor.

Fig. 10 is a plan view of the structure shown in Fig. 9.

Fig. 11 is a sectional view taken substantially along line 11—11 of Fig. 9.

Fig. 12 is a sectional view taken substantially along line 12—12 of Fig. 9.

Fig. 13 is a fragmentary elevational view of the upper end of the stoker, with certain parts broken away to show the general construction of the upper end of one of the tuyère chambers.

Fig. 14 is a sectional view taken substantially along line 14—14 of Fig. 13.

Fig. 15 is a perspective view of one of the ram box cap brackets, and

Figs. 16 and 17 are perspective views, showing the structure of one of the ram box caps.

Referring to the drawings, the numeral 1 indicates generally an inclined grate underfeed stoker, comprising a series of alternately disposed retorts 2 and tuyère rows 3. As shown in Figs. 1 and 9, the stoker is secured to and inclines downwardly from the stoker front and furnace wall 4, and is supported at the lower end thereof upon a transverse I-beam 5. Fuel is supplied to the stoker 1 from the usual hoppers 6, mounted exterior of the front wall, and supported upon ram boxes 7, the fuel gravitating into the inner ends of the cylinders 8 thereof being fed to the stoker through openings or passages 9 provided in the front wall 4 between the adjacent tuyère rows by a series of rams 10. Each inlet opening or passage 9 is bounded at the bottom by a supporting casting 11 having a beveled end 12 forming the bottom of the upper end of the retort 2, at the top by a ram box cap 13 detachably secured to a bracket 14 and at the sides by a pair of wear plates 15. The side walls of each retort 2 comprise a pair of spaced beams 16 extending from front to rear of the stoker upon each of which is supported a series of air cooled supporting plates 17 for the tuyères 3, while the bottom wall consists of a series of alternately disposed secondary fuel feed-ing elements or pushers 18 and dead plates 19.

The under side of the uppermost pusher 18' is provided with a transverse slot 20 in which is secured a downwardly extending bar 21 in which is loosely mounted a rod 22. One end of rod 22 is pivotally secured at 23 to the second pusher 18', while its other end has secured thereto an extension 24 to the free end of which is pivotally connected the upper end of a lever 25. Lever 25 is pivoted on a shaft 26 mounted in a pair of brackets 27, secured to extensions 28 depending from beams 16, as shown in Figs. 1, 2 and 9. The lower end of lever 25 is pivotally connected to one end of a link 29, the other end of the latter being pivotally attached to the upwardly extending portion of a collar 30 mounted on a recipro-cating rod 31. Secured to rod 22 at spaced points on either side of bar 21 by any suitable means, such as by shearing pins, are a pair of collars 32.

45

50

Between collars 32 and bar 21 are a series of removable washers 33 which provide a lost motion connection, if desired, between the first and second pushers 18' and 18². By this arrangement it is seen that upon reciprocation of rod 22 the first two pushers will be actuated. The third pusher 18³ has pivotally connected to the front end thereof a link 34, the free end of which having two or more apertures 35 provided therein adapted for reception of a pin extending through the upper end of a lever 36. The lower end of lever 36 is operatively connected to a second reciprocating rod 31². By providing two or more apertures 35 in link 34 proper adjustment of the pusher may be effected. The third pusher 18³ also has a bar 21³ depending from the lower side thereof through which extends a rod 22³ pivotally connected to the fourth pusher 18⁴. Rod 22³ is also provided with spaced collars 32³ and washers 33³ to permit relative movement of the third and fourth pushers 18³ and 18⁴, if it is so desired. The fifth pusher 18⁵ is operated independently through a link and lever mechanism indicated at 37, and operatively connected to a third pusher 25 rod 31³.

The sixth pusher 18⁶ in the present instance is also provided with a link and lever mechanism 38 similar in construction and operation to those associated with the pushers 18³ and 18⁵ previously described, and is connected by a link 39 to a pusher rod 40 disposed beneath pusher rods 31. The sixth and seventh pushers 18⁶ and 18⁷ are also interconnected for operation by a bar 21⁶ and a rod 22⁶, similar in construction to those previously described. The lowermost pusher 18⁸ in the present instance operates independently through a link and lever mechanism indicated at 41, operatively connected to a pusher rod 40². The extension grates 42 disposed at the lower end 40 of the stoker have each operatively connected thereto a rod 43 to the forward end of which is pivotally connected the lower end of a lever 44 pivoted intermediate its ends on a rod 45, suitably secured to a pair of brackets 46 extending rearwardly from the lower end of front wall 4. The upper end of lever 44 is pivotally connected to one end of a link 47, the other end of the latter being pivoted to the depending portion of a collar 48, secured to a rod 40³. Rods 31 and 40 are mounted in suitable bearings 49 and 50 respectively, secured at one end to the front wall and at the other end to lateral supports 51 provided in brackets 46, by bolts 51', as shown in Figs. 2 and 5. The forward ends of rods 31 and 40 are connected by means of extension rods 52 and 53 respectively to the lower arm 54 of a multi-armed lever 55 pivoted to an extension bracket 56 secured to ram box 7. A second arm 57 of lever 55 has pivotally connected thereto the lower end of a link 58, the upper end of which is connected to a crank 59' on shaft 59, driven by the power mechanism indicated at 60 in a well known manner. A third arm of lever 55 has pivotally connected thereto one end of a link 62, the other end of said link being pivotally connected to the interior of ram 10. Suitable removable washers 63 may be provided on the extension rods 52 and 53 to provide an adjustable lost motion connection between said rods and arm 54, whereby the strokes of pushers 18 may be varied as desired. The specific construction of this connecting means forms no part of the present invention, and therefore need not be described in detail. For a complete disclosure of this construction

reference may be had to United States Patent No. 2,005,005.

From the foregoing description of the rams 10, pushers 18 and extension grates 42, and of the various operating connections between these elements and the power mechanism 60, it is seen that upon rocking of lever 55 by said power mechanism, reciprocatory movement is imparted to said elements. By providing relatively thin dead plates 19 between adjacent pushers 18, groups of said pushers may be interconnected for simultaneous operation if it is so desired. These relatively thin dead plates also enable a larger number of pushers to be provided in each retort, and as a result efficient feeding and distribution of the fuel are effected.

Referring to Figs. 2, 3 and 9 to 11, it is seen that each beam 16 comprises a pair of spaced, longitudinally extending plates 69, 69'. The dead plates 19 and the supporting plate 65 for casting 11 extend between and are secured to the adjacent plates 69 of beams 16 of each retort 2 by any suitable means, such as by welding. By providing welded seams as indicated at 66, between the dead plates and the retort side walls, air leakage into the retorts from the plenum chamber 89 disposed beneath the stoker, is materially reduced. The dead plates 19 are each provided with an enlarged recess 67 at the forward end thereof to accommodate the operating means for the pushers 18, the portions 68 of said dead plates at the sides of these slots providing extended bearing surfaces for said pushers.

As shown more particularly in Figs. 2, 9, 10 and 11, the plates 69 and 69' of each beam 16 are held in spaced relation by means of spacer bars 70, 71, 72 and 73, secured to said plates by a series of bolts 74. The upper edge of each plate 69' extends above the upper edge of plate 69 and has provided therein a series of apertures 75. As illustrated in Figs. 1 and 2, the lower edges of the tuyère supporting plates 17 rest upon the upper edge of plate 69, while laterally extending flanges 76 of said supporting plates rest upon the upper edge of plate 69'. A series of bolts 77 extending through apertures provided in plates 17 and the apertures 75 of plates 69' rigidly retain said supporting plates in position in such a manner that the vertical faces 18 thereof are flush with the retort side of plates 69. The plates 17 are also held together by means of tie plates 79. A bracket 80, having an extension 81, is secured to the lower end of each plate 69'. The extensions 81 of the brackets 80 in line with the walls of adjacent retorts are secured by means of bolts 82 to hollow rectangular bearing blocks 83, which rest upon rollers 84 mounted in roller brackets 85 secured by bolts 86 to I-beam 5. The rollers 84 provide an anti-friction support for the lower end of the stoker permitting said stoker to expand and contract due to the variable temperature conditions under which it operates.

The stoker front 4 is supported upon a transverse I-beam 90, and comprises a series of spaced columns 91 and 92, extending from I-beam 90 to substantially the lower end of the brickwork 93 forming the front wall 4' of the furnace. The columns 91 may be of I-beam construction, while columns 92 comprise pairs of channel irons 94 having filler plates 95 disposed therebetween. The webs of adjacent channel irons 94 are secured by the bolts 96, or by any other suitable fastening means. This construction enables the stoker to be constructed in units of any desired 75

number of retorts. The columns 91 and 92 are machined at the upper ends 97 thereof to conform with the interior configuration of a transversely disposed channel iron 98, Fig. 6. A trans-

versely extending plate 99 rests upon the web of channel iron 98 and has secured thereto a pair of longitudinally extending angle irons 100 and 101. One leg of angle iron 100 is secured to channel iron 98 by bolts 102 or by any other suitable means.

The outer facing of the stoker front comprises a sheet metal closing plate 103 which is secured to the flanges 91' and 94' of I-beams 91 and channel irons 94, respectively, by rivets 105, or by any other suitable securing means, as shown more particularly in Fig. 5. The upper end of closing plate 103 is also secured to angle iron 101 by bolts 106. As shown in Fig. 6, the front portion of brickwork 93 is supported upon plate 99, while the inner portion thereof is supported upon the upper surface of alternately disposed ram box cap and wall brackets 14 and 87, respectively. Brackets 14 are secured at the forward ends thereof to the closing plate 103 by bolts 107, or by any other suitable securing means.

The ram boxes 7 have provided at the inner ends thereof flanges 108 which are secured by bolts 109 to the front closing plate 103 in such a manner that the ram cylinders 8 thereof communicate with the inlet openings 9 of the stoker front 4. Some of the bolts 109 extend through the flanges 91' and 94' of columns 91 and 92, thereby affording a rigid support for the ram boxes 7. Closing plate 103 has provided opposite each retort 2 of the stoker a pair of vertically spaced apertures 110 and 111, Figs. 5 and 6, the apertures 110 being shaped to conform with the inner end of ram cylinders 8. The apertures 111 provide openings for the reciprocating rods for the pushers 18 and extension grates 42. A pair of bearing brackets 112 and 113, in which are mounted the bearings 49 and 50, respectively, for the reciprocating rods are secured to closing plate 103 and to the flanges 91' and 94' of columns 91 and 92 by bolts 112' and 113'.

The lower ends of columns 91 and 92 are secured by welding to the base flange of a transversely extending angle iron 114, the lower, outwardly disposed sides of said columns being cut away so as to accommodate the vertical flange of said angle iron. Suitable filler plates 115 are provided between angle iron 114 and the top flange of I-beam 90 and bolts 88, Figs. 1 and 9, passing through said flange, filler plates and angle iron rigidly secure said columns in position. A substantially arcuate guard plate 116 extends transversely of the stoker front at the lower extremity thereof and acts as a seal to prevent the escape of draft air from the plenum chamber 89. The upper end of plate 116 and the vertical flange of angle iron 114 are secured to the lower end of closing plate 103 by bolts 117.

Referring more particularly to Figs. 2, 4, 7, 9 and 10, it is seen that the upper ends of plates 69' are secured by rivets 118, or by any other suitable securing means, to the rearwardly extending flanges 119 of angle irons 120, which in turn are secured to the rear flanges 121 and 122 respectively, of columns 91 and 92 by bolts 123. The upper end of the stoker is thus rigidly secured directly to the stoker front, and the use of intermediate brackets is entirely eliminated.

The brackets 46 provided near the lower inner end of stoker wall 4 are welded or otherwise se-

cured to the rearwardly extending flanges of angle irons 125 which in turn are secured by bolts 126 to the rear flanges 121 and 122 of columns 91 and 92, respectively.

The wear plates 15 constituting the side walls 5 of the inlet openings 9 are secured by bolts 127 to vertical supporting plates 128, as shown more particularly in Figs. 2, 4 and 7. Plates 128 extend beyond the upper and lower extremities of plates 15 and are secured by bolts 129 to ears 130 integral with columns 91 and 92. Supporting plates 128 are each provided with a vertical flange 131 at the forward end thereof against which the forwardly disposed ends of wear plates 15 abut. As shown in Fig. 7, the inner walls of wear plates 15 converge slightly from front to rear, as indicated at 132, whereby the fuel fed through openings 9 is introduced to the retorts in a compact mass.

The castings 11 forming the bottom walls of 20 openings 9, are each provided with an open transverse slot 135 at the forward end thereof which receives a tongue 136 projecting rearwardly from closing plate 103, Figs. 1, 6 and 7. The forward ends of castings 11 are thus held against vertical 25 movement. A stud bolt 137 engaging in a tapped recess in supporting plate 65 prevents vertical, as well as transverse movement of the other end of said casting. Castings 11 are thus rigidly held in position, while the securing means therefore 30 permits ready installation or removal thereof in the event they should become worn or damaged during operation of the stoker.

Referring more particularly to Figs. 1, 4, 6, and 13 to 17 inclusive, each ram box cap extension 35 bracket 14 is of a hollow substantially triangular boxlike construction having an upwardly and rearwardly inclined wall 133 terminating at its upper end in a detachable, vertically disposed fuel abutting portion 134, a substantially vertical forward wall 135, and substantially vertical side walls 136 and 137. The top wall 138 of bracket 14 comprises a pair of substantially flat parallel portions 139 and 140 connected by an inclined portion 141, forming a depression 142 at the forward 45 end thereof into which extend the flanges of channel iron 98. Portion 139 is disposed somewhat beneath the upper edge of fuel portion 134, the purpose of which will be hereinafter described. The inclined wall 133 is provided with a pair of 50 apertures 143 and 144, near the lower end thereof for receiving a pair of locking lugs 145 and 146 respectively provided near the lower end of ram box cap 13, Figs. 6, and 13 to 17. The portion of the wall 133 of bracket 14 disposed forwardly of 55 apertures 143 and 144 provides a pair of tongues 147 which, in assembly, engage the lugs 145 and 146, thereby effectively holding the forward end of the ram box cap in position. Inclined wall 133 has also provided therein an enlarged opening 60 148, which in assembly may be closed by a plate, not shown, to prevent air leakage into the retorts, and a pair of bolt receiving recesses 149 and 150. Recesses 149 and 150 each comprises an enlarged portion 151 and a reduced portion 152 communicating therewith. The enlarged portions 151 of apertures 149 and 150 are of sufficient size to accommodate the heads of bolts 153. The inner wall 154 of recesses 149 and 150 is spaced sufficiently from the inner surfaces of the flanges 154' 70 adjacent reduced portions 152 to permit the heads of bolts 153 to pass therebetween, as shown in Fig. 6. The upper end of ram box cap extension 13 is provided with a pair of apertures 155 adapted to receive bolts 153. A pair of guide lugs 156 75

are also provided on extension 13 which in assembly engage the side walls 157 of recess 148. To assemble the caps 13 on brackets 14, the lugs 145 and 146 are first inserted in apertures 143 and 144, after bolts 153 have been inserted in recesses 149 and 150, as shown in Fig. 6. Extension 13 is then swung upwardly, causing the shank of bolts 153 to enter apertures 155. Nuts 158 are then secured to bolts 153 and extension 13 is then drawn tightly into engagement with bracket 14. The fuel engaging portion 159 of each ram box cap extension 13 in the present instance is of substantially arcuate construction, although it may be flat or angular, as desired, while the side walls 160 thereof are substantially flat and in assembly lie substantially in abutting relation with the retort side walls.

As shown more particularly in Figs. 4 and 15, the side walls 136 and 137 of each bracket 14 are provided near the upper ends thereof with flat, outwardly projecting portions 161 and 162 respectively, the lower edges 163 of which, in assembly, rest upon the upper horizontal edges 163' of the upper tuyère supporting plates 164, thereby affording a support for the rearwardly disposed ends of said brackets.

The rearwardly disposed end of each bracket 14 is also supported at either side thereof by a pair of bars 165, Figs. 4, 6, 13 and 14. These bars 30 extend through aligned apertures 166 and 167 provided respectively in the side walls 136 and 137 of each bracket 14 and in the upper tuyère supporting plates 164 of the stoker. The upper surfaces of bars 165 lie in substantially abutting relation with the lower surface of a flange 168 integral with and extending forwardly of the inner surface of wall 133 of bracket 14. Bolts 169 passing through apertures provided in flange 168 and bars 165 rigidly secure said bars to the bracket. The bars 165 engaging the upper tuyère supports 164 thus also form effective supports for the rearwardly disposed ends of brackets 14.

The upper fuel abutting portion 134 of each bracket 14 is detachably secured in position by 45 means of stud bolts 170 engaging in tapped recesses provided in a flange 171, depending from the upper wall portion 139. Other securing means may also be provided if it is so desired. Thus, in the event any of the portions 139 should 50 become damaged during operation of the furnace, it may be readily removed without disturbing adjacent parts.

The wall brackets 87 disposed between adjacent brackets 14 are also of hollow construction 55 and each comprises a substantially flat top wall 172 upon which the brickwork 93 is supported, a front wall 173, vertical side walls 174, and a substantially flat bottom wall 175, Figs. 4 and 13. Each side wall 174 of brackets 87 has provided 60 thereon an extended lateral projection 176 which in assembly rests upon the upper portion 139 of an adjacent bracket 14. The upper end of each tuyère support 164 is provided with a longitudinally extending flange 177 projecting into the 65 associated tuyère chamber. The bottom wall 175 of each bracket 87 extends forwardly of front wall 173, and terminates on a line substantially midway between the front and rear ends of said bracket. In assembly bottom wall 175 rests upon 70 the flanges 177 of a pair of tuyère supporting plates 164 and is secured thereto by bolts 178. The brackets 87 are thus rigidly held in position.

The upper tuyères 179 of each row are held 75 against vertical displacement by adjustable locking bars 180. Each bar 180 is provided with a

pair of vertical slots 181 through which extend a pair of bolts 182. Bolts 182 also extend through apertures provided in the vertical flanges 183 of tuyère supports 164 and in a retaining bar 184 disposed in vertical alignment with the front wall 173 of bracket 87. Bars 180 may thus be adjusted vertically until the lower ends thereof engage tuyères 179 when the nuts 185 at the end of said bolts are tightened, thereby securing said bars in locking engagement with said tuyères. 10

From the foregoing description it will be observed that a highly improved stoker has been provided. The structural framework of the retort and front wall is not only rugged, but involves a simplified construction. The elements 15 of the stoker which are subject to wear, such as the tuyère supports, the ram box caps, the wear plates and the wall brackets, are so mounted that installation thereof may not only be readily made, but renewals of such parts may be made in the 20 event damage should occur thereto without disturbing, to any great extent, the adjacent parts.

While the embodiment herein shown is admirably adapted to fulfill the objects primarily stated, it is to be understood that the invention 25 is not to be limited thereto, since it may be embodied in other forms, all coming within the scope of the claims which follow.

What is claimed is:

1. In a stoker, the combination with a series 30 of alternately disposed retorts and tuyère rows, each of said retorts comprising a pair of spaced, longitudinally extending beams, of a series of alternately disposed pushers and dead plates provided at the bottom of each of said retorts, a 35 stoker front comprising a series of spaced columns in line with said tuyère rows, flanges provided at the forwardly and rearwardly disposed sides of said columns, means for securing said beams to the flanges provided at the rearwardly 40 disposed sides of said columns, a front closing plate having a pair of vertically spaced openings therein opposite each of said retorts and secured to the flanges at the forwardly disposed sides of 45 said columns, ram boxes secured to said closing plate in alignment with the upper of said openings, operating means for said pushers extending through the lower of said openings in said closing plate, bearings for said operating means, means for securing one end of each of said bearings to said closing plate, extension brackets provided on said columns, and means for securing the other end of said bearings to said extension brackets. 50

2. In a stoker, the combination with a series 55 of alternately disposed retorts and tuyère rows, of a furnace wall, a stoker front adapted to support said furnace wall, said stoker front comprising a series of spaced columns having flanges at the forwardly and rearwardly disposed sides 60 thereof, means for securing said retorts to the flanges provided at the rearwardly disposed sides of said columns, a front closing plate secured to the flanges provided at the forwardly disposed sides of said columns, a transverse channel beam 65 secured to the upper ends of said columns, means provided on said channel beam for supporting the outer portion of said furnace wall, an angle iron secured to the lower ends of said columns, a rigid support for said columns, means for securing said angle iron to said rigid support, and a transverse sealing plate secured to the lower 70 end of said closing plate and engaging said rigid support. 75

3. In a stoker, the combination of a series of 75

inclined alternately disposed retorts and tuyère rows, each of said retorts consisting of a pair of spaced, longitudinally extending beams, a row of tuyère supporting plates mounted on each of said beams, each of the uppermost of said tuyère supporting plates having a vertical flange extending laterally from one end thereof, adjustable bars mounted adjacent the flanges of pairs of said last mentioned tuyère supporting plates and adapted to engage the uppermost tuyères of said rows to prevent vertical displacement thereof, and means for securing said adjustable bars in position.

4. In a mechanical stoker, the combination with a series of inclined, alternately disposed retorts and tuyère rows, each of said retorts comprising a pair of spaced beams, of a stoker front, comprising a series of spaced columns having flanges at the forwardly and rearwardly disposed sides thereof, means for securing said beams to the flanges at the rearwardly disposed sides of said columns, a front closing plate secured to the flanges provided at the forwardly disposed sides of said columns, ram boxes secured to said closing plate and in alignment with said retorts; a series of spaced ram box cap brackets, means for securing the forwardly disposed end of each of said brackets to said closing plate, ram box caps mounted on said brackets, tuyère supporting plates secured to said beams, means for securing the rearwardly disposed end of each of said brackets to said tuyère supporting plates, a series of wall brackets alternating with said first mentioned brackets, flanges extending on either side of each of said wall brackets and resting upon the upper surface of said ram box cap brackets, and means for securing the lower ends of said wall brackets to said tuyère supports.

5. A ram box cap bracket of substantially triangular construction, having front, rear, top and side walls, said rear wall inclining upwardly and rearwardly, and having a plurality of apertures therein adapted to receive locking means provided on a ram box cap, said top wall comprising a pair of flat parallel portions arranged in offset relation, and connected by an inclined portion, supporting means for said bracket projecting laterally from each of said side walls, and a detachable, fuel abutting portion secured to one end of said bracket and forming an extension of the said inclined wall thereof.

6. In a stoker, the combination with a series of alternately disposed retorts and tuyère rows, each of said retorts comprising a pair of spaced, longitudinally extending beams, of a plurality of alternately disposed pushers and dead plates provided in the bottom of each of said retorts, tuyère supporting plates mounted on said beams, a stoker front, comprising a series of spaced columns having laterally extending flanges at the forwardly and rearwardly disposed sides thereof, means for securing said beams to the flanges at said rearwardly disposed sides of said columns, a

front closing plate having vertically spaced pairs of openings provided therein in alignment with said retorts, secured to the flanges at the forwardly disposed sides of said columns, ram boxes secured to said closing plate in alignment with the upper of said openings provided therein, operating means for said pushers extending through the lower of said openings in said closing plate, bearing brackets for said operating means secured to said closing plate, and said stoker front having passages communicating with said retorts and in line with the upper of said openings in said closing plate, said passages being bounded at the bottoms thereof by fuel supporting castings, at the top by ram box caps, and at the sides by wear plates.

7. In a stoker, the combination with a series of alternately disposed retorts and tuyère rows, of a furnace wall, a stoker front for supporting said furnace wall, said stoker front comprising a series of spaced columns having flanges at the forwardly and rearwardly disposed sides thereof, means for securing said retorts to the flanges provided at the rearwardly disposed sides of said columns, a front closing plate secured to the flanges provided at the forwardly disposed sides of said columns, a transverse channel beam secured to the upper ends of said columns, means provided on said channel beam for supporting the outer portion of said furnace wall, a series of brackets supporting the inner portion of said furnace wall, and means for supporting said brackets in position.

8. In a mechanical stoker, the combination with a series of inclined, alternately disposed retorts and tuyère rows, each of said retorts comprising a pair of spaced beams, of a stoker front, comprising a series of spaced columns having flanges at the forwardly and rearwardly disposed sides thereof, means for securing said beams to the flanges provided at the rearwardly disposed sides of said columns, a front closing plate secured to the flanges provided at the forwardly disposed sides of said columns, ram boxes secured to said closing plate and in alignment with said retorts, a series of spaced ram box cap brackets, ram box caps mounted on said brackets, each of said brackets being secured at one end to said closing plate, tuyère supporting plates secured to said beams, projections provided on either side of said brackets engaging the upper edges of said tuyère supporting plates, a pair of locking bars secured to each bracket and extending through apertures provided in adjacent tuyère supporting plates for further supporting said brackets, a series of wall brackets alternating with said first mentioned brackets, flanges extending on either side of said wall brackets and resting upon the upper surfaces of said ram box cap brackets, and means for securing the lower ends of said wall brackets to said tuyère supporting plates.
